Primary Examiner — John A Voytek*(74) Attorney, Agent, or Firm* — Shaun J. Fox(57) **CLAIM**

The ornamental design for a tire, as shown and described.

DESCRIPTION

FIG. 1 is a side perspective view of a tire showing a first embodiment of our new design;
FIG. 2 is a front elevational view thereof;
FIG. 3 is a side elevational view of the right side thereof;
FIG. 4 is a side elevational view of the left side thereof;
FIG. 5 is an enlarged fragmentary view thereof;
FIG. 6 is a side perspective view of a tire showing a second embodiment of our new design;
FIG. 7 is a front elevational view thereof;
FIG. 8 is a side elevational view of the left side thereof;
FIG. 9 is a side elevational view of the right side thereof; and,
FIG. 10 is an enlarged fragmentary view thereof.
In the drawings, the broken lines depict environmental subject matter only and form no part of the claimed design.

1 Claim, 10 Drawing Sheets(56)
